UNITED STATES PATENT OFFICE.

GREGORY C. DAVISON AND CECIL P. CAULKINS, OF NEW LONDON, CONNECTICUT, ASSIGNEES, BY MESNE ASSIGNMENTS, TO AMERICAN ORDNANCE CORPORATION, OF NEW YORK, N. Y., A CORPORATION OF DELAWARE.

LINE-THROWING GUN.

Application filed May 14, 1919, Serial No. 297,129. Renewed June 2, 1924.

To all whom it may concern:

Be it known that we, GREGORY C. DAVISON and CECIL P. CAULKINS, citizens of the United States, both residing at New London, in the county of New London and State of Connecticut, have invented certain new and useful Improvements in Line-Throwing Guns; and we do hereby declare the following to be a full, clear, and exact description 10 of the invention, such as will enable others skilled in the art to which it appertains to make and use the same.

Our invention relates to guns intended to throw a line from the deck of a stranded vessel to the shore, or from the shore to a stranded vessel, or from one vessel to another, for lifesaving or other salvage purposes.

With such guns neither a long range or 20 high pressures are at all necessary, and it is especially desirable to provide a gun and ammunition therefor, the operation of which will not require any special degree of mechanical skill, or any large amount of practice; and it is also desirable to provide a 25 cheap and efficient gun and ammunition therefor which are not likely to get out of order, and which may be readily kept in repair, and at all times kept ready for use 30 when desired.

Our invention will be more fully understood after reference to the accompanying drawings, in which like parts are indicated by similar reference symbols throughout the 35 several views, and in which:—

Figure 1 shows a side elevation of the complete piece, the fixed ammunition therefor being shown in dotted lines, and parts being shown broken away.

Figure 1^a shows a section through the housing block for the firing pin, parts being shown in elevation and the scale being larger than in Figure 1.

Figure 2 is a plan view of the rear portion 45 of the gun body showing parts of the firing mechanism carried thereby, the gun body being detached from the mount, and the parts being shown on a larger scale than in Figure 1.

Figure 3 is a front elevation of the gun carriage showing the gun and the parts car-

ried thereby, and the cap-square bolts removed; and

Figure 4 is a plan view of the gun carriage shown in Figures 1 and 3. 55 A represents the gun body, which is preferably made of cast steel, or iron, with a smooth bore A⁰ provided at its rear end with a hollow hemispherical chamber a⁰, the rear end of the bore being closed by the 60 housing block for the firing pin, which will be hereinafter described.

The gun body is provided with the usual trunnions A', and near its breech it is provided with two upwardly projecting lugs 65 A² for the firing mechanism, which will be hereinafter described, and also with a downwardly projecting lug A³, perforated as at a to receive the elevating lock pin which will be hereinafter described. 70

The gun body is mounted on a wheeled carriage which will now be described.

B represents a casting which may be made of cast steel, gun metal, or other suitable material, having a base plate B' and suitable 75 angular lugs b projecting down therefrom, and adapted to engage in the upper surface of the gun platform W, which may be the deck of a ship, the ground, or any suitable support for the gun carriage. 80

Projecting upwardly from this plate B' and integral therewith, are the two brackets B², which are provided at their upper ends with bearings b' for the trunnions A' of the gun, and with screw-threaded holes b² adapted to 85 engage the screw-threaded ends of the cap-square bolts C' which pass through holes c in the cap-squares C.

The casting B is also provided with upwardly projecting ribs B³, which are bored, 90 as are also the corresponding portions of the brackets B², to permit the insertion of the studs D on which the wheels E are journaled. These studs are held in place by the tapered pins F. 95

The gun carriage normally rests on the wheels E and on the lug b, as shown in Figure 1. The brackets B² are provided with a series of oppositely disposed holes b³, adapted to receive the elevating lock pin G, 100 which is provided with a handle G', and is preferably provided with a lock chain G².

to prevent its loss when not in position on the mount. The holes b^3 are so arranged as to give variable elevation to the gun, and in the drawings in Figure 1 we have shown them arranged to give the gun an elevation of 45° , 60° or 80° , as may be preferred.

To secure lightness of the parts, the side brackets may be provided with openings b^4 , b^5 and b^6 , as shown in Figure 1.

- 10 The opening in the breech of the gun is closed by the housing block H, which is screw-threaded at its forward end, as at h , to engage in the corresponding screw threads on the gun body, and is chambered to receive 15 the firing pin K, and the withdrawal spring I for the firing pin. The forward end of the firing pin passes through the annular nut h^2 which is screwed into the forward end of the housing block, and serves not 20 only to close the forward end of the firing pin chamber, but also serves as an abutment for the withdrawal spring I.

The rear end of the spring I bears against the annular rib h on the firing pin, the rear 25 face of which rib h is coned as at h' , and serves as a valve to engage the valve seat h' formed in the housing block H. Thus, when the charge is fired in the gun, the firing pin serves as a valve to close the opening rear- 30 ward through said housing, in which the firing pin slides axially.

The lugs A^2 are perforated as at a^2 , and form therewith bearings for the hammer bolt L in which is made fast to the hammer M 35 in any convenient way, as by means of the pin N. The hammer M has a hollow arm, weighted as at m , and provided with the finger hole m' for convenience in cocking the hammer.

40 The hammer is also provided with a notch m^2 to engage the loop p of the hammer spring P, which spring is coiled as at p' around the hammer bolt L, and has its ends p^2 engaging the corresponding abutments in 45 the lugs A^2 .

The short arm n^3 of the hammer, when 50 in the cocked position, engages the lower face of the toe q of the sear piece Q, which sear piece is made fast to the sear bolt R in any convenient way, as by means of the pin N' . This sear bolt passes through bearings a^3 in the lugs A^2 . The arm q' of the sear piece Q is normally pressed downwards by the sear springs S, which is generally 55 similar to the hammer spring P' already described, but may be made less powerful if desired.

The loop s of this sear spring engages the notch q^2 of the sear Q, and the coils s' of the sear spring are wound around the sear bolt R, and the ends s^2 of the sear spring engage suitable abutments on the lugs A^2 .

The travel of the toe q of the sear Q is limited by the sear stop pin U.

65 The arm q' of the sear Q is provided with

a hole q^0 in which engages the hook t of the firing lanyard T, as shown in dotted lines in Figure 1.

The gun is especially designed for use with fixed ammunition of the type shown 70 in our application filed of even date here-with serially numbered 297,130, and entitled Improvements in fixed ammunition for use with line throwing guns, which ammunition is shown in dotted lines in Figure 1, and 75 comprises a projectile X, and a cartridge case Y containing the propelling charge having a primer y adapted to be struck by the firing pin K. The other end of the projectile is provided with an eye x to which 80 the line Z is attached.

The operation of the device is as follows:—

The piece is set at the desired elevation, which may be done by swinging the gun 85 about its trunnions and inserting the elevating lock pin G in the corresponding holes b^3 ; said pin, of course, passing through the hole a in the lug A^3 projecting downwardly from the gun body. Now cock the piece by 90 inserting one of the fingers in the finger hole m' , and pulling the hammer to the rear until it occupies the position shown in full lines in Figure 1.

The rearward movement of the hammer 95 will cause the arm m^3 of the hammer piece to press down the toe q of the sear Q against the action of the sear spring, and when said arm m^3 clears the toe q the sear will snap back into the position shown in Figure 1; 100 and if the hammer be released the piece will be in the cocked position, and it will be impossible to fire same without either breaking the stop pin U, or pulling on the arm q' of the sear Q.

Of course, the lanyard would not be applied until the moment of firing, so that there would be no likelihood of accident from the premature pulling on the lanyard.

The piece being cocked, the retracting 110 spring I will withdraw the point of the firing pin into the concave chamber a^0 at the base of the bore A^0 . Now, if the fixed ammunition is loaded into the gun, the cartridge case Y cannot be forced down far 115 enough to strike the firing pin being stopped by the concave walls of the chamber a^0 , and the firing pin will be held by said spring I clear of the primer y. The piece will now be cocked and ready for firing.

To fire the gun, insert the hook t of the lanyard T into the eye q^0 of the arm q' of the sear Q, and pull rearward on the lanyard. The toe q of the sear will press down the arm m^3 of the hammer piece M, and when the toe clears said arm, the hammer will be free to fly forward under the pressure of the hammer spring, and the weighted arm m will strike the rear end of the firing pin K, forcing said pin forward 125 130

against the action of the spring I and causing the point of the firing pin to strike the primer y and explode the propelling charge in the cartridge case Y.

- 5 When the gun is fired, the projectile X will travel along the bore, unwinding the line Z from the reel, not shown. As the projectile continues its flight through the air, the rearward pull of the line Z will cause 10 the projectile to tumble or turn through 180°, and then the projectile will follow its trajectory with its eye x to the rear, and the weighted end foremost; at the same time dragging out the line Z, which line will 15 serve to retain the eye x in the rearward position, and will tend in a measure to guide or steer the projectile in its flight.

- As these guns are intended to be fired at a high elevation, the downward thrust would 20 ordinarily equal or exceed the horizontal pressure of the recoil, and this downward pressure will cause the lugs b to bite into the gun platform and prevent the carriage from recoiling through any lateral distance. 25 The piece may be brought to the original firing position relative to the gun platform by pressing down on the gun body, tilting the rear end of the carriage clear of the gun platform, and rolling the piece forward 30 on the wheels E.

- In the same way, the gun may be trained through any desired angle by pressing down on the gun body, and lifting the lugs b clear of the gun platform, and then swinging the 35 axis of the bore to the right or left, as desired.

- In a similar way, the gun may be transported from place to place by tilting up the rear end of the base plate B' and running the carriage around on its wheels E.

- With guns of this character no high initial velocity is desired, and the gun may be made of cheap cast metal, and the body of the carriage also may be made of cast metal; but if desired the brackets B² may be secured to the base plate B' and suitably braced thereon, instead of being cast integral therewith, if desired, but we prefer to have the brackets and the base plate 50 formed of an integral casting.

- With the construction herein described, very little machining or finishing is required, and practically none of the expensive work ordinarily experienced in fitting breech mechanisms to guns is needed.

- Thus it will be seen that we provide a cheap, simple and efficient device for use for the purposes described, which does not require any special skill to operate, which is not liable to get out of order, or to need repair, and which may be kept in serviceable shape with very little attention.

- It will be obvious that various modifications might be made in the herein described 65 apparatus, and in the construction, combina-

tion and arrangement of parts which could be used without departing from the spirit of our invention, and we do not mean to limit the invention to such details except as particularly pointed out in the claims.

70

Having thus described our invention what we claim and desire to secure by Letters Patent of the United States is:—

1. A line throwing gun comprising a gun body having a smooth bore, with a concave 75 chamber at the rear end thereof, too narrow to permit the entrance thereto of the base of the cartridge case, a firing pin having its firing point normally projecting part of the way into said concave chamber and having 80 its base projecting rearwardly through the walls of the piece, a retraction spring normally pressing said firing pin backwards, a spring impressed hammer pivoted to the gun body and adapted to strike said firing pin and throw it forward against the action of said retraction spring, and means for cocking said hammer and for releasing same when desired, substantially as described.

2. A line throwing gun comprising a gun 90 body having a smooth bore, with a concave chamber at the rear end thereof, too narrow to permit the entrance thereto of the base of the cartridge case, a firing pin having its firing point normally projecting part of 95 the way into said concave chamber and having its base projecting rearwardly through the walls of the piece, a retraction spring normally pressing said firing pin backwards, a spring impressed hammer pivoted to the gun body and adapted to strike said firing pin and throw it forward against the action of said 100 retraction spring, the said hammer being provided with a short cocking arm, a spring impressed sear having a toe engaging said 105 cocking arm, and a lever arm for tripping same, substantially as described.

3. A line throwing gun comprising a gun body having a smooth bore, with a concave 110 chamber at the rear end thereof, too narrow to permit the entrance thereto of the base of the cartridge case, a firing pin having its firing point normally projecting part of the way into said concave chamber and having its base projecting rearwardly 115 through the walls of the piece, a retraction spring normally pressing said firing pin backwards, a hammer pivoted to the gun body, a loop spring normally pressing on said hammer tending to cause it to strike said firing pin and throw it forward against the action of said retraction spring, and a spring impressed sear for cocking said hammer and for releasing same when desired, 120 substantially as desired.

4. A line throwing gun comprising a gun body having a smooth bore, with a concave 125 chamber at the rear end thereof, too narrow to permit the entrance thereto of the base of the cartridge case, a firing pin having 130

its firing point normally projecting part of the way into said concave chamber and having its base projecting rearwardly through the walls of the piece, a retraction spring normally pressing said firing pin backwards, a hammer pivoted to the gun body, a loop spring normally pressing on said hammer tending to cause it to strike said firing pin and throw it forward against the action of said retraction spring, the said hammer being provided with a short cocking arm, and a spring impressed sear having a toe engaging said cocking arm, and a lever arm

for tripping said sear, substantially as described.

5. In ordnance, the combination of a gun barrel having a firing pin mounted for reciprocal movement in an opening at the breech thereof, said pin having a pointed forward end and means on said pin rearwardly of said pointed forward end and seated in a direction opposite the direction of firing movement of said pin for normally sealing the opening in which the pin moves.

GREGORY C. DAVISON.
CECIL P. CAULKINS.
